COMBINED CLOCK FACE AND PICTURE FRAME

Marion K. Summers, W. Commerce St.,
Brownstown, Ind. 47223

Filed Jan. 30, 1970, Ser. No. 21,160

Term of patent 14 years

Int. Cl. D10—01

U.S. Cl. D42—7

Fig 1

Fig 3

Fig 4

Fig 2

FIG. 1 is a front elevational view of a combined clock face and picture frame, showing my new design.

FIG. 2 is a top plan view thereof;

FIG. 3 is a front elevational view of a modification thereof, and

FIG. 4 is a front elevational view of another modification thereof.

I claim:

The design for a combined clock face and picture frame, substantially as shown and described.
